UNITED STATES PATENT OFFICE.

SAMUEL J. CHAMBERS, OF HASTINGS, NEBRASKA.

BENCH-CLAMP.

No. 911,028.

Specification of Letters Patent.

Patented Feb. 2, 1909.

Application filed March 28, 1908. Serial No. 423,937.

To all whom it may concern:

Be it known that I, SAMUEL J. CHAMBERS, a citizen of the United States, residing at Hastings, in the county of Adams and State 5 of Nebraska, have invented a new and useful Bench-Clamp, of which the following is a specification.

This invention relates to clamping devices, and particularly to the kind used by 10 carpenters and wood workers for fastening a board or block to a work bench.

One object of this invention is to provide 15 a clamp which will be positively held against sliding movement when fastened to a bench. This is especially desirable during the operation of sawing or planing, where there is a tendency with most clamps now in use to slide forward, due to the pressure exerted on the object held by the clamp.

20 Another object of this device is to provide a smooth clamping surface, such as will not have a tendency to deface the material held clamped.

With these and other objects in view, as 25 will more fully hereinafter appear, the invention consists in certain novel features of construction and arrangement of parts, herein- after fully described, illustrated in the accompanying drawings, and particularly pointed 30 out in the appended claim, it being understood that various changes in the form, proportions, size and minor details of the structure may be made without departing from the spirit or sacrificing any of the advan- 35 tages of the invention.

In the accompanying drawings:—Figure 1 is a perspective view of the device. Fig. 2 is a side view of the device showing the position of the parts when applied to the ordinary 40 bench used by carpenters and disclosing the means for clamping the board or block.

Similar numerals of reference are employed to indicate corresponding parts throughout the several figures of the draw- 45 ings.

The clamp proper is preferably formed of a single piece of steel bent in the form of an elongated U, the space between the arms 1 and 2 being sufficient to permit the arms to 50 straddle the apron 3 of a bench, table or the like. On the inner face of the arms 1 and adjacent the end thereof are formed spurs 4 lying in a vertical plane projecting at right angles to the inner face of the arm, the function 55 of which will presently appear.

The outer arm 2 of the device is of slightly greater length than the arm 1, and on the end thereof is formed a work-holder comprising a base plate 5 of slightly greater width than the arm 2, the inner end of which is 60 flush with the inner face of the arm 2, and on the outer end of the plate is formed a wall 6 extending upwardly at right angles to the base plate 5. Directly beneath the work holder on the arm 2 is formed a perforation 65 for the reception of a pivot bolt 8 which extends transverse of the arm, and on either end spurs or levers 9, the pivoted ends of which are enlarged and curved inwardly sufficient to lie approximately flush with the 70 inner face of the arm 2 when the levers are on the center. The handle portion of the lever curves downwardly and outwardly away from the heads for a length sufficient to extend beyond the arm 2, and is removably 75 connected by a bolt 11. A spur is formed on that portion of each lever which lies flush with the inner face of the arm 2 and extends into the space between the two arms. With this construction it is obvious that as the lever is raised, the spur 10 is eccentric with the pivot 8 to be lifted from the recess, and when the arms 1 and 2 are adjustable on the opposed faces of the apron 3 by forcing the lever downward, the spur 10 enters the space 80 and further pressure forces the arms acting on the pivot 8 as a fulcrum close together, the spurs 4 and 10 embedding the apron 3 and the holder clamping the block and the top 12 with the table. 90

What is claimed is:—

A clamping device embodying a U-shaped member adapted to straddle the apron of a bench, table or the like, and having spurs formed on the inner face of one arm thereof, 95 a work holder on one arm of said member having a vertical wall disposed beyond the vertical plane of said arm, a lever pivotally mounted on the last named arm having an enlarged head provided with a spur adapted 100 to engage the table or bench apron, so as to prevent movement of the member.

In testimony that I claim the foregoing as my own, I have hereto affixed my signature in the presence of two witnesses.

SAMUEL J. CHAMBERS.
